COMBINATION SQUARE

Austin L. Stowell, New Britain, Conn., assignor to
The Stanley Works, New Britain, Conn., a corporation of Connecticut

Application May 28, 1931, Serial No. 540,659

4 Claims. (Cl. 33—103)

This invention has to do with the art of so-called "adjustable" or "combination" squares and is more particularly concerned with those devices in which the head may be clamped to or removed from the blade. An adjustable square of the type involving the present invention comprises head and blade members together with suitable clamping instrumentalities for operatively associating these parts. Ordinarily, the head is provided with a channel in which is slidably fitted one edge of the blade, and the clamping instrumentalities are arranged so that the head may be clamped to the blade at any desired point.

One of the now known devices of this type permits the blade to be disengaged from the head so as to allow for independent use of these members by merely loosening the clamping bolt. The blade, when removed, may be used as a scale or straight edge, and the head, itself, may be used separately to gauge the inside of a 45° angle. The disadvantage of this construction arises from the fact that, not infrequently, the blade, when the clamping bolt is released, will accidentally slide out of the head and become lost. Another type of combination square now available on the market is disclosed in the patent to Bodmer No. 1,213,578 issued January 23rd, 1917 and owned by the assignee of the present application. This arrangement has the advantage of preventing accidental loss of the blade, when the clamping bolt is untightened, and also the advantage of permitting the blade to be swung from one side of the tool stock over to the opposite side thereof without disassembling the parts, but it has the disadvantage of not permitting of the separation of the blade and the head without a complete removal of the clamping nut which is liable to become lost or misplaced, as is also the bolt with which it is associated.

Bearing in mind the foregoing, this invention has in view the provision of an adjustable square which combines the advantageous features of the construction referred to and wherein the described disadvantages inherent in those structures are overcome and eliminated. In carrying out this thought, the arrangement is such as to permit of sliding movement between the parts so that the blade may be longitudinally adjusted in the ordinary use of the square; the blade may be swung from one side of the head to the other side without detaching the blade, and the blade may be entirely removed from the square head at will, all without any danger of accidentally losing the blade or parts of the bolt mechanism.

An important object of the invention is to pro-

vide an improved square of this type wherein the parts are so arranged and correlated that the clamping instrumentalities are always connected to and carried by the head regardless of whether or not they have been adjusted to permit removal of the blade or adjustment of the blade, and the blade is held against accidental removal when the clamping instrumentalities have been adjusted to permit only sliding movement between the blade and the head.

Other objects will be in part obvious and in part pointed out more in detail hereinafter.

The invention accordingly consists in the features of construction, combination of elements and arrangement of parts which will be exemplified in the construction hereinafter set forth and the scope of the application of which will be indicated in the appended claims.

For a full and more complete understanding of the invention, reference may be had to the following description and accompanying drawings, wherein:

Figure 1 is a plan view of a combination square made in accordance with one embodiment of the present invention, dotted lines bringing out a position of the head during the assembling of these parts;

Fig. 2 is an individual showing of the head. This view is a section through the head taken about on the plane indicated by the line 2—2 of Fig. 5;

Fig. 3 is a plan view, somewhat diagrammatic, of a portion of the blade and head, developing the manner in which these two parts are assembled or taken apart;

Fig. 4 is a perspective illustration of the clamping bolt and nut carried thereby;

Fig. 5 is a detailed front view of the head;

Fig. 6 is a view similar to Fig. 1 but showing another embodiment of the invention; and

Fig. 7 is a sectional view taken on line 7—7 of Fig. 6.

Referring to the drawings, the square is shown as having a head, which is designated generally by the reference character A. The blade of the square is designated B in the embodiment shown in Figs. 1 to 5, and B' in the embodiment shown in Figs. 6 and 7. The blade, in each instance, may be of any suitable dimensions, and it has each edge calibrated, as shown at 1 and 2. In each embodiment, the blade has a longitudinally extending channel, preferably along its medial portion, and this channel has a stop or abutment at each end. In Fig. 1, the blade B is shown as having a channel in the form of a slot 3 extend-

ing substantially from a point midway of the extremities of the blade to a point referred to as 4, which is spaced a distance from one end of the blade which is slightly less than the distance between either of the side edges and the slot 3, this for a purpose later to be described in detail. The ends of the slot constitute stops. In the embodiment shown in Fig. 6, the channel in the blade is in the form of a longitudinal groove 3' in one side thereof. This groove has, adjacent each end, a stop 4' which may be formed by separate stud portions, but the stops are preferably formed by making small integral projections in the groove, as by extruding the metal into the groove from the opposite side of the blade. The groove, by preference, is curved in cross section, although this is not necessary.

The head A is shown as comprising edge portions 5 and 6 which are connected by structure 20 designated 7 and the edge portion 8 which is perpendicular to the edge 5. The portions 5 and 6 are disposed at an angle of 45° with respect to one another whereby they are constituted a mitre gauge. A groove 9 is formed in the edge portion 8 and this groove is designed to receive the blade B.

The structure 7 includes a cross-piece 10 and a web 11 which is divided to provide the groove 9. The portion 10 is enlarged as shown at 12 and this enlarged portion is bored to provide an opening in alignment with a corresponding opening in the web 11, which opening is defined by deformed portions 13 of the web 11 on each side of the groove 9. A clamping bolt 14 is slightly reduced in diameter at one end as shown at 14a and this end is provided with an enlarged or flanged head 15. The other end of the bolt 14 is cut away as shown at 16 and a projection or pin 17 extends from the flattened surface of the cut-away portion. Intermediate the portion 15 and 16, the bolt 14 is provided with threads as shown at 18. A nut 19 is carried by the bolt 14 and is adapted to slide over the portion 14a or be screwed onto the threads 18.

By referring to Figs. 1 and 6, it will be noted that, when the bolt 14 is positioned in the bores of the portions 12 and 13, the framework 7 will prevent withdrawal of the bolt in one direction, while the nut 19 prevents withdrawal in the other direction. The nut 19 is retained on the bolt by the head 15 and a cross-piece 10.

When the device is in its assembled position, the projection 17 extends into the slot 3 (or the groove 3') and the nut 19 is tightened against the cross-piece 10 to securely clamp the head A against the blade. When the head and blade are to be adjusted, the nut 19 may be unscrewed slightly to permit of this relative sliding movement. When the parts are to be disassembled, the nut 19 is entirely unscrewed from the threads 18 and moved out over the reduced portion 14a. The head A is then moved longitudinally along the blade B until the projection 17 reaches the end of the slot 3, whereupon the head may be swung over into the dotted line position of Fig.

1. In this position, the end of the blade is disposed entirely outside of the groove 9 and may be moved laterally to completely disengage the head from the blade. When the parts are to be again assembled, these operations are reversed. Regardless of whether the head and blade are assembled, the bolt 14 and nut 19 are always carried by the head A and any liability of their becoming misplaced or lost is obviated.

From the foregoing description, taken in con-

nnection with the accompanying drawing, it will be seen that, in each embodiment, the blade may be longitudinally adjusted by slightly untightening the nut 19 and then tightening it up again after the adjustment has been made. When making such adjustment, there is no likelihood of the blade coming loose from the head for, in the event the blade should tend to drop down due to gravity, the engagement of the projection 17 against one of the stops in the channel would prevent the blade from being disengaged. When it is desired to swing the blade from one side to the other, this may be readily done as previously described. When it is desired to remove the blade, the nut can be unscrewed from the threaded portion 18 and the head brought to the dotted line position shown in Fig. 1 and in which position the blade is clear of the slot 9. The blade and the head can then be used separately. The nut and the bolt cannot become displaced from the head. Thus, the objects of the present invention are obtained.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. In a tool of the character described, a head provided with a groove, a blade slidably mounted in said groove and having a channel closed at each end, a bolt carried by said head and having a projection engaging in said channel, and a nut threaded on said bolt, said bolt being formed with means for permanently retaining the nut thereon.

2. In a tool of the character described, a head provided with a groove, a blade slidably mounted in said groove and having a longitudinally extending channel closed at each end, a bolt carried by said head and having, adjacent one end, a projection adapted to engage in said channel, and a nut threaded on said bolt, the other end of said bolt being headed to hold the nut permanently on the bolt.

3. In a tool of the character described, a head having a groove, a blade one edge of which is adapted to engage in said groove and is adapted to be clamped against the bottom of said groove, said blade having a longitudinally extending channel closed at each end, a bolt carried by said head and having a threaded portion between its ends, a flat portion provided with a projection engaging in said channel and a reduced portion at its other end flanged at its extremity, and a nut on said bolt.

4. In a tool of the character described, a head having mitre faces disposed at an angle of 45 degrees and a surface connecting said faces and perpendicular to one of them, said last mentioned face being formed with a groove therein, a bolt having a screw threaded portion carried by the head, a clamping nut for said bolt, means for retaining the bolt on the head and rendering the same movable relative to the head comprising a head on the bolt and a shank portion of reduced diameter between said screw threaded portion

and said head passing through said nut, said bolt being formed with a projection substantially perpendicular thereto, and a blade adapted to be received by said groove and having a closed channel extending longitudinally thereof, the projection on the bolt being adapted to fit in said chan-

nel, the distance between one end of the channel and the end of the blade being less than the distance between one side of the blade and the channel.

AUSTIN L. STOWELL. 5
